HAROLD O. PETERSON, OF RIVERHEAD, NEW YORK, ASSIGNOR TO RADIO CORPORATION OF AMERICA, A CORPORATION OF DELAWARE

ELIMINATION OF FADING BY DIVERSITY FACTOR

Application filed June 19, 1925. Serial No. 38,165.

This arrangement relates to the use of an apparatus designed to tend to prevent and reduce the effects of the phenomenon commonly known as fading of wireless signals when received by a single receiver, and also to eliminate to more or less extent the interference caused by static and other stray disturbances.

It is well known that when a receiving set is sharply tuned to a single wave length, and is receiving signals from a transmitter which is also sharply tuned to the same wave length a considerable distance away, difficulty is often had with the signals dying down and becoming inaudible at various intervals. In some localities this is a very general phenomenon while in others it occurs less frequently. The arrangement of this invention is intended to overcome this difficulty and can be used with long wave lengths or with short ones, though probably its most important use will be found with the shorter wave lengths, because with these the trouble is especially prevalent and most annoying.

Long wave lengths have been most commonly used for long distance communication up until very recently. However, it has been found that short wave lengths used for sending and receiving by wireless have advantages not found with the longer ones. For instance, there is less static disturbance, less absorption and the directional effects produced in directional antennæ systems is much sharper and better defined. With the former arrangements, however, reliable operation on short waves has been very difficult over long distances and often times practically impossible, because of fading, even though over short distances short waves can be used with success.

Various theories regarding the phenomenon of fading have been advanced. Perhaps one of the better known and apparently logical ones is that based on the "Heaviside layer" theory. This theory assumes that above the surface of the earth there is a layer of stratified and partially conducting air or atmosphere of some sort which has a reflective effect upon wireless waves impinging on

it. Since it is true that there are some waves which travel on the surface of the earth and others which extend upwardly, that path taken by the upwardly extending waves, after having been reflected by the "Heaviside layer", will be greater in length than that taken by the waves travelling on or near the surface. Therefore there is a possibility that the upwardly extending waves will be some distance behind in phase, relative to those that extend along the surface, when they meet.

For this reason the waves meeting at the receiving point may be 180 degrees out of phase, and if they are equal in magnitude, no signal will be had, for the two waves will cancel each other. It will be readily seen that this will not occur at all points along the surface of the earth where receiving stations may be located, hence, if reception can be had from several places at the same time and the results of the reception brought to a central point, the effect of fading at any one receiver will be reduced. This invention deals with arrangements for producing these results.

Prior arrangements for obtaining directional signalling and for reducing the effect of static have used a plurality of antennæ and have attempted to combine the various signal energies directly and in phase or to heterodyne them to produce beats and then to combine the beats directly and in phase. These schemes have not been very successful in combating fading, and the difficulty seems to lie in the impossibility of combining the energies in phase, for the relative phases of the signal energies at the different antennæ is a variable.

An explanation of this is suggested by the "Heaviside layer" theory, for although a strata of conducting atmosphere lies considerable distance above the surface of the earth, this layer is by no means stationary. Particularly at daybreak and sunset when the sun's rays are increasing or diminishing, is this effect most noticeable. It is suggested that this is due to the ionizing effect of the sun's rays. At night, the "Heaviside layer" rises to a height considerably above that in

the day time, and even during the day or night slight variations in the height and surface of the layer is probable. The result of this is considerable variation in location, 5 phase, and intensity of signals received, being the common experience of fading recognized by those familiar with radio reception.

It has been found that fading in the longer 10 wave lengths varies slowly, while the shorter ones vary very rapidly and in a disturbing way probably caused by the unstationary surface of the layer and undulations in it. This accounts for the greater difficulties experienced with shorter waves.

This invention also has for its purpose the use of several antennæ for averaging up and producing a signal which will vary only in proportion to the number of antennæ used, 20 but the resulting signals are combined independently of the phase of the received high frequency signal energy. Variation caused by the action described will produce an averaging result on the several antennæ. If a 25 large number of points are taken, separated a number of wave lengths apart on a direct line from the sending station, the chance of fading at all of these places at the same time is small.

30 When high frequencies are sent over ordinary transmission lines for any appreciable distance the effect of attenuation must be taken into consideration. Thus, if a wave of varying intensity and high frequency be 35 sent considerable difficulty will be had in keeping the various intensities separated. In this invention the frequency is reduced by means of modulation to a point at which it can more easily be transmitted.

40 As was already remarked, it has been found that the waves impinging upon two antennæ separated any appreciable distance apart are not always in phase with each other nor does the phase relation between the two 45 remain the same at different times. When two antennæ are so located, at times the wave will vary in phase in a very undesirable way. For instance, when the wave length of 100 meters is used and the two antennæ are separated several miles apart, a complete phase 50 reversal between the two stations has sometimes been found to take effect every few seconds. This remarkable phenomenon prevents adjusting phases for direct combination of the signal waves produced, and I 55 have devised methods for combining the signal energies independently of phase, which methods are here enumerated and more fully explained later:—

60 1. Modulation of the signal at the receiver by audio frequency energy generated at a central station.

2. Generation of a second high frequency at the receiver, modulating it with audio frequency energy generated at a central station,

and sending only the audio frequency modulation back to central station.

3. Generation of modulated high frequency at the central station, transmitting it to the receivers, and returning only the 70 modulation to the central station.

With audio modulation at the receivers the audio frequency will exist in the output whenever signals exist at any given receiver, 75 irrespective of radio frequency phase differences for these are negligibly small relatively to the audio frequency period. With this method the undesirable effects of attenuation, high frequency phase differences, etc., are avoided because the sending of the signal 80 over the transmission lines at a low frequency is not affected by these. Also detection and amplification may be had at each antenna and transmission and combination 85 of the resulting audio frequencies had as before.

It has been found that so far as a practical application of this invention goes that when a frequency is used in the neighborhood of 100 meters for sending and a separation of 90 antennæ a distance of 500 feet or less than two wave lengths, an appreciable improvement may be had. If more antennæ are used and various other distances of separation are used, a proportionally greater improvement 95 will be found. Thus, within a small area considerably better reception is possible when used with short wave lengths.

Wherever local or territorial fading is in 100 advance known to exist use may be made of this knowledge. Thus in some places where localized fading is present, small separation of antennæ would be sufficient. Other places where very generally fading is the rule, separation at greater distances would be necessary. However, where general fading is 105 present and greater separation of the antennæ is required this greater separation would take care of difficulty encountered in case the fading should become more or less localized. This idea of different fading and different 110 phase relations is called the principle of "diversity factor" of the various places and relations in question.

To accomplish these results the following 115 arrangements are disclosed and reference is made to Figs. 1 to 4 inclusive of the annexed drawings.

Fig. 1 shows a general method of carrying 120 out my invention.

Fig. 2 shows a substitute arrangement for one of the receiving stations.

Fig. 3 shows a modification of this substitute arrangement.

Fig. 4 shows an arrangement whereby the 125 same transmission line may be used for both receiving and transmitting the modulating frequency.

1, 2, 3, etc., represent a series of geographically spaced antennæ and may or may not be 130

separated by distances greater than one wavelength apart. These antennæ systems are coupled to the modulators 4, 5 and 6 which are controlled by the couplings 7, 10, 8, 11 and 5 9, 12 through a transmission line 13. The output from a source of audio frequency, or of a radio frequency which is modulated at an audio rate, is sent over this transmission line as indicated at 22.

10 Thus, the result of the signal received on the antennæ and the modulating wave is had in the couplings 14, 15 etc. These oscillations are detected as at 16, 17, etc. and appear in the output circuits 18, 19, 20, etc. The 15 audio frequency will not appear when no signal is received because the modulators 4, 5, etc. are balanced. The output circuits are all coupled to the return transmission line 21 to which is connected the receivers or 20 equivalent signal translating arrangement 23.

Whenever a signal is received on the antennæ, the oscillations produced are modulated by an audio frequency or both a radio 25 frequency and an audio frequency. With this arrangement the audio frequency appears in the output circuits of the detectors only when the signal affects the antennæ. Various objects and advantages can readily be seen in 30 this arrangement. For instance, the effect of attenuation is decreased, and the phase relations of the various audio frequency outputs is maintained more nearly constant than with other similar methods heretofore used. 35 For all practical purposes the audio frequency phase variations caused by radio frequency phase variations of the received signals is so slight as to be negligible.

Various other arrangements can be used 40 for modulating the oscillations as received on the antennæ.

Fig. 2 shows one of these other methods. 24 may be one of the receiving antennæ to which is coupled an intermediate frequency modulator 25, the modulating coil being shown at 26.

From any suitable local or central source 50 high frequency oscillations are introduced at 27, causing an intermediate frequency wave to appear in the coupling 28 to the intermediate frequency amplifier 29. This is coupled through couplings 30 to a balanced modulator 31 which is modulated through the couplings 32, 33 at an audio rate. The intermediate frequency components of the audio 55 modulated frequency appears in the output coupling 34 and is led to a detector 35 which may be connected to the transmission line from 36. In this case the high frequency modulation is separated from the audio frequency modulation so that a greater range of control may be effected on the receiving system.

60 The different modulating arrangements can be either located at the respective receiv-

ers or may be at the central receiving stations thereby permitting individual control of the antennæ stations from a local point.

Another method of accomplishing this same 70 result is shown in Fig. 3.

Here the antenna arrangements 37 are coupled to a modulator 38. This modulator is affected through its coil 39 by a local high frequency oscillator 40. Audio frequency is impressed upon this oscillator through the 75 couplings 41, 42 so that the oscillations affecting the modulator tube are, in turn, modulated at an audio rate.

The output of the modulator 38 is transmitted through the coupling 43 into the intermediate frequency amplifier 44 which, with its output coil 45, may be coupled to a detector 46. This detector produces the audible signals in the connections 47 which may be transmitted over a transmission line to the central receiving station or used in any other 80 advantageous arrangement.

Thus, when a signal is received on the antenna 37, it is impressed on the modulator circuit 38 and results in an intermediate frequency output. If we assume that the audio frequency is represented by f_3 , that the frequency produced in the high frequency oscillator 40 is f_2 , and the frequency of the received signal is f_1 , then we have in the output coil 43 of the modulator 38, the frequencies $f_1 - f_2$ and $f_1 - f_2 \pm f_3$. All these frequencies appear in the detector 46, but the output of this detector gives only f_3 which is the original audio frequency introduced at 42. 95

In the case of the arrangement in Fig. 2 if the signal frequency is f_1 , the high frequency impressed, f_2 , then there appears in the output circuit of the modulator 25 the frequency $f_1 - f_2$. Assuming that f_3 which is induced at 33 is an audio frequency tone then the modulator 31 will have in its output coil 34 the same frequencies as were found in the case of Fig. 3 and the detection is carried out by detector 35 in a like manner producing the audio frequency output f_3 at 36. 105

If it is desirable to use only one transmission line, an arrangement can be used as in Fig. 4 where 1', 2' etc. are the antennæ and 4', 5', etc., are the intermediate frequency, modulator and amplifier. These intermediate frequency modulators are supplied by a modulated heterodyne frequency at the coupling 7', 10' and 8', 11' over the connections 48 and 49 through the condensers 55, 56 and 57, which permit only the high frequencies generated at 59 to pass through. Choke coils 52 and 53 are arranged to prevent these frequencies from affecting the other parts of the system. Thus, proper modulated frequencies are found at 14', 15' and are detected at 16', 17' giving the desired low audio frequencies at 18', 19', which are coupled to the transmission line at 54. These 110 separately received signals are combined in 120 123

translating arrangement 60. Audio modulated high frequency may be induced at 59 to give the proper signal tone.

The antennæ 1', 2', etc. may be separated at a distance greater than one wave length of the signal which they are intended to receive. The spacing is chosen to confine the dimensions of the receiving system to that found most effective within a minimum space. The operation of this arrangement for reducing fading is thought to be obvious, and it has the further advantage that wherever several independently operated and separated receiving stations are used considerable of the effect of static and other disturbances is eliminated. This is true because usually such disturbances are of more or less local nature and the ratio of the total signal received at the central receiving station 60 is by far greater when a local disturbance affects only one of the several antennæ than it would be if only one antenna were used and the total effect of the disturbance were felt on this antenna. In this way the greater the number of antennæ and the more diversely located they are, the greater the advantage of this system will be. This is true both in respect to static and similar disturbances and to fading.

It is obvious that either of the arrangements or modifications shown in Figs. 2 and 3 might well be used in connection with the single transmission line arrangement shown in Fig. 4 without departing from the spirit of this invention. Other minor and obvious modifications and substitutions may also be made. The locations of the various oscillating systems and modulating circuits need not be limited as shown but may well be arranged at any desired place.

With these arrangements, the troublesome effects from attenuation over long distance transmission lines when high frequency is used are obviated. It can be seen from this arrangement that reception at various points different distances from each other is had, and is centralized at a common point to produce a better result. For fading occurring at any one of these stations at different times an average result is produced which causes the relative intensity at the receiver to be practically constant. This can be accomplished only when a considerable number of antennæ are used and distributed according to the known conditions of that particular locality. At some points it might be found necessary to use only two antennæ stations, as shown, since it might be found that fading would not be present at the same time at these points.

While I have described my invention in a more or less specific way, it is not intended to limit it to these particular arrangements. In the claims which follow I shall by the term "signal initiated energy" mean energy which

is present only when a signal is received, and I intend it to include signal energy, amplified signal energy, and heterodyned signal energy.

What I claim is:—

1. The method of receiving signal oscillations which includes intercepting the signal oscillations at various points, generating an audio frequency oscillation at another point, transmitting the audio frequency oscillation to the various points, combining the audio frequency with signal initiated oscillations, and detecting and transmitting the result to the central point and translating it there. 70

2. In combination, several high frequency receiving stations separated by a distance greater than one wave length of the frequency intended to be received, an audio frequency receiving station, transmission lines connecting the high frequency stations and the audio frequency stations, a source of high frequency and of audio frequency oscillations coupled to the transmission lines, combining means at the high frequency stations for combining the two high frequencies and audio frequency whereby the combination may be detected and returned over the transmission lines to the audio frequency station. 80

3. The method of diversity factor reception for reducing fading effects at relatively short wave lengths which includes collecting signal energy at a plurality of separated points, at each of said points modulating signal initiated energy with generated audio frequency energy, detecting the modulated energies to reproduce audio frequency energies, combining the audio frequency energies, and translating the combined energy. 95

4. The method of diversity factor reception for reducing fading effects at relatively short wave lengths which includes collecting signal energy at a plurality of separated points, at each of said points modulating signal initiated energy with generated audio frequency energy, suppressing the audio frequency components of the modulated energies, detecting the higher frequency components of the modulated energies to reproduce audio frequency energies only when signal energy is received, combining the audio frequency energies, and translating the combined energy. 105

5. The method of diversity factor reception for reducing fading effects at relatively short wave lengths which includes collecting signal energy at a plurality of separated points, generating audio frequency energy at a central point, using the audio frequency energy to modulate signal initiated energy at each of said separated points, detecting the modulated energies to reproduce audio frequency energies, combining the audio frequency energies, and translating the combined energy. 120

6. The method of diversity factor reception for reducing fading effects at relatively 130

short wave lengths which includes collecting signal energy at a plurality of separated points, generating audio frequency energy at a central point, using the audio frequency to 5 modulate signal initiated energy at each of said points, suppressing the audio frequency components of the modulated energies, detecting the higher frequency components of the modulated energies to reproduce audio frequency energies only when signal energy is received, combining the audio frequency energies, and translating the combined energy.

7. The method of diversity factor reception for reducing fading effects at relatively short wave lengths which includes collecting signal energy at a plurality of separated points, combining the signal energies with generated heterodyne energy at each of said 10 points, modulating the combined energies with generated audio frequency energy, detecting the modulated energy to reproduce audio frequency energies, combining the audio frequency energies, and translating the 25 combined energy.

8. The method of diversity factor reception for reducing fading effects at relatively short wave lengths which includes collecting signal energy at a plurality of separated points, combining the signal energies with generated heterodyne energy at each of said 30 points, modulating the combined energies with generated audio frequency energy, suppressing the audio frequency components of the 35 modulated energies, detecting the higher frequency components of the modulated energies to reproduce audio frequency energies only when signal energy is received, combining the audio frequency energies, and translating the 40 combined energy.

9. The method of diversity factor reception for reducing fading effects at relatively short wave lengths which includes collecting signal energy at a plurality of separated 45 points, heterodyning the signal energy at each of said points with generated heterodyning energy, generating audio frequency energy at a central point, using the audio frequency energy to modulate the combined energies at each of said separated points, detecting the modulated energies to reproduce audio frequency energies, combining the audio frequency energies, and translating the combined energy.

55 10. The method of diversity factor reception for reducing fading effects at relatively short wave lengths which includes collecting signal energy at a plurality of separated points, heterodyning the signal energy at 60 each of said points with generated heterodyning energy, generating audio frequency energy at a central point, using the audio frequency energy to modulate the combined energies at each of said separated points, suppressing the audio frequency components of the 65

the modulated energies, detecting the higher frequency components of the modulated energies to reproduce audio frequency energies only when signal energy is received, combining the audio frequency energies, and translating the combined energy. 70

11. The method of diversity factor reception for reducing fading effects at relatively short wave lengths which includes collecting signal energy at a plurality of separated points, generating audio frequency energy at a central point, generating high frequency energy at a central point, combining the centrally generated energy with the signal energy at each of said separated points, detecting the combined energies to reproduce audio frequency energies, combining the audio frequency energies, and translating the combined energy. 75

12. The method of diversity factor reception for reducing fading effects at relatively short wave lengths which includes collecting signal energy at a plurality of separated points, generating audio frequency energy at a central point, generating high frequency energy at a central point, combining the centrally generated energy with the signal energy at each of said separated points, suppressing the audio frequency components of the combined energies, detecting the higher frequency components of the combined energies to reproduce audio frequency energies only when signal energy is received, combining the audio frequency energies, and translating the combined energy. 80

13. The method of diversity factor reception for reducing fading effects at relatively short wave lengths which includes collecting signal energy at a plurality of separated points, generating audio frequency energy at a central point, generating high frequency energy at a central point, using the high frequency energy to heterodyne the signal energies at each of said separated points to produce intermediate frequency energy, modulating the intermediate frequency energies with the audio frequency energy, detecting the modulated intermediate frequency energies to reproduce audio frequency energies, combining the audio frequency energies, and translating the combined energy. 85

14. The method of diversity factor reception for reducing fading effects at relatively short wave lengths which includes collecting signal energy at a plurality of separated points, generating audio frequency energy at a central point, generating high frequency energy at a central point, using the high frequency energy to heterodyne the signal energies at each of said separated points to produce intermediate frequency energy, modulating the intermediate frequency energies with the audio frequency energy, suppressing the audio frequency components of the modulated energies, detecting the higher frequency 90

quency components of the modulated energies to reproduce audio frequency energies only when signal energy is received, combining the audio frequency energies, and translating the combined energy.

15. An arrangement for diversity factor reception for reducing fading effects at relatively short wave lengths comprising means for collecting signal energy at a plurality of separated points, means for modulating the signal initiated energies with generated audio frequency energy, means for detecting the modulated energies to reproduce audio frequency energies, means for combining the audio frequency energies, and means to translate the combined energy.

16. An arrangement for diversity factor reception for reducing fading effects at relatively short wave lengths comprising means for collecting signal energy at a plurality of separated points, balanced modulators for modulating the signal initiated energies with generated audio frequency energy and for suppressing the latter, means for detecting the modulated energies to reproduce audio frequency energies when signal energy is received, means for combining the audio frequency energies, and means to translate the combined energy.

17. An arrangement for diversity factor reception for reducing fading effects at relatively short wave lengths comprising means for collecting signal energy at a plurality of separated points, a central source of audio frequency energy, means for modulating the signal initiated energies at each of said points with the audio frequency energy, means for detecting the modulated energies to reproduce audio frequency energies, means for combining the audio frequency energies, and means to translate the combined energy.

18. An arrangement for diversity factor reception for reducing fading effects at relatively short wave lengths comprising means for collecting signal energy at a plurality of separated points, a central source of audio frequency energy, a balanced modulator at each of said points for modulating the signal initiated energies with the audio frequency energy and for suppressing the latter, means for detecting the modulated energies to reproduce audio frequency energies when signal energy is received, means for combining the audio frequency energies, and means to translate the combined energy.

19. An arrangement for diversity factor reception for reducing fading effects at relatively short wave lengths comprising means for collecting signal energy at a plurality of separated points, means to combine the signal energies with generated heterodyne energy at each of said points, means for modulating the combined energies with generated audio frequency energy, means for detecting the modulated energies to repro-

duce audio frequency energies, means for combining the audio frequency energies, and means to translate the combined energy.

20. An arrangement for diversity factor reception for reducing fading effects at relatively short wave lengths comprising means for collecting signal energy at a plurality of separated points, means to combine the signal energies with generated heterodyne energy, a balanced modulator at each of said points for modulating the combined energies with generated audio frequency energy and for suppressing the latter, means for detecting the modulated energies to reproduce audio frequency energies when signal energy is received, means for combining the audio frequency energies, and means to translate the combined energy.

21. An arrangement for diversity factor reception for reducing fading effects at relatively short wave lengths comprising means for collecting signal energy at a plurality of separated points, means to heterodyne the signal energy at each of said points, a central source of audio frequency energy, means for modulating the combined energies with the audio frequency energy, means for detecting the modulated energies to reproduce audio frequency energies, means for combining the audio frequency energies, and means to translate the combined energy.

22. An arrangement for diversity factor reception for reducing fading effects at relatively short wave lengths comprising means for collecting signal energy at a plurality of separated points, means to heterodyne the signal energy at each of said points with generated heterodyning energy, a central source of audio frequency energy, a balanced modulator at each of said points for modulating the combined energies with the audio frequency energy and for suppressing the latter, means for detecting the modulated energies to reproduce audio frequency energies when signal energy is received, means for combining the audio frequency energies, and means to translate the combined energy.

23. An arrangement for diversity factor reception for reducing fading effects at relatively short wave lengths comprising means for collecting signal energy at a plurality of separated points, a central source of audio frequency energy, a central source of high frequency energy, means for combining the centrally supplied energy with the signal energy at each of said points, means for detecting the combined energies to reproduce audio frequency energies, means for combining the audio frequency energies, and means to translate the combined energy.

24. An arrangement for diversity factor reception for reducing fading effects at relatively short wave lengths comprising means for collecting signal energy at a plurality of separated points, a central source of audio

frequency energy, a central source of high frequency energy, means to combine the centrally supplied energy with the signal energy at each of said points and for suppressing the 5 audio frequency energy, means for detecting the combined energies to reproduce audio frequency energies when signal energy is received, means for combining the audio frequency energies, and means to translate the 10 combined energy.

25. An arrangement for diversity factor reception for reducing fading effects at relatively short wave lengths comprising means for collecting signal energy at a plurality of 15 separated points, a central source of audio frequency energy, a central source of high frequency energy, means to heterodyne the signal energies with the high frequency energy to produce intermediate frequency 20 energies, means for modulating the intermediate frequency energies with the audio frequency energy, means for detecting the modulated intermediate frequency energies to reproduce audio frequency energies, means 25 for combining the audio frequency energies, and means to translate the combined energy.

26. An arrangement for diversity factor reception for reducing fading effects at relatively short wave lengths comprising means 30 for collecting signal energy at a plurality of separated points, a central source of audio frequency energy, a central source of high frequency energy, means to heterodyne the signal energies with the high frequency 35 energy to produce intermediate frequency energies, a balanced modulator at each of said points for modulating the intermediate frequency energies with the audio frequency energy and for suppressing the latter, means 40 for detecting the modulated energies to reproduce audio frequency energies when signal energy is received, means for combining the audio frequency energies, and means to translate the combined energy.

45. 27. The method of diversity reception for reducing fading effects at relatively short wave lengths which includes making a plurality of radio frequency energy collections having relatively different fading characteristics, transforming each of the collected energies into a form which is independent of the phase of the received radio frequency energy, combining the transformed energies, 50 and translating the combined energy.

28. The method of diversity reception for reducing fading effects at relatively short wave lengths which includes making a plurality of radio frequency energy collections 55 of relatively different fading characteristics, locally generating energy, separately utilizing each of the collected energies for controlling the flow of locally generated energy independently of the phase of the received radio frequency energy, combining the re-

sulting energies, and translating the combined energy.

29. The method of diversity reception for reducing fading effects at relatively short wave lengths which includes making a plurality of radio frequency energy collections of relatively different fading characteristics, locally generating audio frequency energy, separately utilizing each of the collected energies for controlling the flow of the locally 75 generated audio frequency energy independently of the phase of the received radio frequency energy, combining the resulting energies, and translating the combined energy.

30. A diversity receiving system for reducing fading effects at relatively short wave lengths comprising a plurality of antennæ having relatively different fading characteristics, means for separately transforming each of the received energies into a form 80 which is independent of the phase of the received radio frequency energy, means to combine the transformed energies, and means to translate the combined energy.

31. A diversity receiving system for reducing fading effects at relatively short wave lengths comprising a plurality of antennæ having relatively different fading characteristics, a local source of energy, means responsive to each of the collected energies for separately controlling the flow of the locally generated energy independently of the phase of the received radio frequency energy, means to combine the resulting local energies, and means to translate the combined energy.

32. A diversity receiving system for reducing fading effects at relatively short wave lengths comprising a plurality of antennæ having relatively different fading characteristics, a local source of audio frequency energy, means responsive to each of the collected energies for separately controlling the flow of the locally generated energy independently of the phase of the received radio frequency energy, means to combine the resulting local energies, and means to translate the combined energy.

33. The method of diversity reception for reducing fading effects at relatively short wave lengths which includes making a plurality of radio frequency energy collections having relatively different fading characteristics, transforming each of the collected energies into energies which may be additively combined independently of the phase of the received radio frequency energy, combining the transformed energies, and translating the combined energy.

34. The method of diversity reception for reducing fading effects at relatively short wave lengths which includes making a plurality of radio frequency energy collections having relatively different fading characteristics, locally generating alternating electrical energy, transforming each of the collected 125 130

energies, with the aid of the locally generated energy, into energies which may be additively combined independently of the phase of the received radio frequency energy, combining the transformed energies, and translating the combined energy.

35. A diversity receiving system for reducing fading effects at relatively short wave lengths comprising a plurality of antennæ having relatively different fading characteristics, means for collecting radio frequency energy, means for transforming each of the collected energies into energies which may be additively combined independently of the phase of the collected radio frequency energy, means to combine the transformed energies, and means to translate the combined energy.

36. A diversity receiving system for reducing fading effects at relatively short wave lengths comprising a plurality of antennæ having relatively different fading characteristics, means for collecting radio frequency energy, a local source of energy, means for transforming each of the collected energies, with the aid of the locally generated energy, into energies which may be additively combined independently of the phase of the radio frequency energy collected, means to combine the transformed energies, and means to translate the combined energy.
